UNITED STATES PATENT OFFICE.

WILLIAM P. CALLAHAN, THOMAS DE ARMON, AND WILLIAM K. CALLAHAN, OF DAYTON, OHIO; WILLIAM K. CALLAHAN EXECUTOR OF SAID WILLIAM P. CALLAHAN, DECEASED.

METHOD OF RE-PRESSING OIL-MEAL INTO SOFT CAKES.

SPECIFICATION forming part of Letters Patent No. 727,897, dated May 12, 1903.

Application filed May 12, 1902. Serial No. 106,945. (No specimens.)

To all whom it may concern:

Be it known that we, WILLIAM P. CALLAHAN, THOMAS DE ARMON, and WILLIAM K. CALLAHAN, citizens of the United States, residing at Dayton, in the county of Montgomery and State of Ohio, have invented certain new and useful Improvements in Apparatus for and Methods of Re-Pressing Oil-Meal into Soft Cakes; and we do declare the following to be a full, clear, and exact description of the invention, such as will enable others skilled in the art to which it appertains to make and use the same, reference being had to the accompanying drawings, and to the letters of reference marked thereon, which form a part of this specification.

This invention relates to improvements in methods of re-pressing ground oil meal or flour into cakes of suitable density or hardness for stock-feed.

The oil-cake after it comes from the oil-press in which it is compressed for the purpose of extracting the oil is of a very solidified nature and is too hard to be bitten and masticated by stock. It is therefore the object of this invention to re-press the oil-meal or flour which has been ground from such solidified cakes into a cake of less hardness or density.

The object is to give the subsequent cake only a sufficient pressure to cause the particles of meal or flour to compress into a cake of suitable hardness, or, in other words, a cake that may be broken by the stock in eating the same.

It will be understood that it is desirable to feed the product to stock in this condition in order to avoid waste. Were the product to be fed to the stock in bulk in the form of meal or flour, it will be readily seen that a great waste would occur owing to the wind and to the stock itself scattering the same. By feeding the meal or flour to stock in the form of cakes of such density or hardness that they may be broken by the stock in eating the same this waste is avoided.

Another object in preparing the oil meal or flour in this manner lies in the economy and convenience of shipping the same as compared to shipments of the meal or flour

in bulk. In carrying out our process of re-pressing the oil meal or flour into cakes for the purposes outlined above we employ means for suitably heating the material which, as before stated, is in the form of meal or flour which has been ground from the solidified cakes as they come from the oil-press, these cakes, as before stated, being entirely too hard for stock-feeding purposes; and, further, means for automatically feeding or delivering the oil meal or flour in a suitably-heated condition to a press, in which said meal or flour is pressed into cakes of suitable hardness and density to hold the particles in one integral mass or form—namely, a cake.

The process therefore consists of, first, in heating said meal or flour which has been ground from the hard cake to a suitable condition to give it a proper adhesive nature; second, in next delivering said oil meal or flour in such heated condition to a carrier; third, in re-pressing said oil meal or flour into a soft cake or a cake of proper hardness for stock-feeding purposes only.

The machine through the instrumentality of which we are enabled to carry out our process and to obtain the desired results is illustrated in the accompanying drawings, of which—

Figure 1 is a side elevation. Fig. 2 is a sectional plan view on the line xx of Fig. 1. Fig. 3 is a detail sectional view of the movable head or cover; Fig. 4, an enlarged sectional view of a portion of the press. Fig. 5 is an enlarged vertical sectional view of the charging-box.

In the specification similar reference-letters indicate corresponding parts.

The material consists of oil meal or flour which has been previously ground from solidified cakes of great density, is introduced to a heater A, wherein it is cooked to a suitable condition, and is moistened by a jet of steam or water entering said heater through a pipe B. When the meal or flour is properly cooked, it is in a suitable condition for the formation of the soft cake. From the heater A the said material is delivered through a charging-spout C into a reciprocating charging-box D. The box D receives motion

through the medium of gearing consisting of a spur-wheel E and a pinion F and slotted cross-head or yoke H, in which works a crank I, connected by a wrist-pin J. Power is communicated to said gearing through friction-pulley K, which runs loosely when the charging-box D is not in operation; but when it is desired to charge the press L the operator presses a foot-lever M, which throws the clutch mechanism and the friction-pulley into gear, thus carrying through the gearing the crank I and the slotted cross-head or yoke H, the charging-box D moving forward and delivering its contents to the press N. The press L consists of a cylinder O, which contains a ram or plunger P. (Shown in dotted lines in Fig. 1.) Four upright tie-rods Q tie the head-block R to the cylinder O by means of nuts R', which fit on the screw-threaded ends of said tie-rods. The press N, as shown in Fig. 4, is secured within the press-frame, so that the platen T, which rests on top of the ram or plunger P, may have proper movement up and down. When the press is ready for charging, the platen T is at the proper distance below the top of the press N to admit a sufficient quantity of meal or flour to make a cake of the desired weight. The charging-box D is moved forward to fill the space above the platen T. After this space is filled a division-plate S is placed on top of the meal so placed. By means of a properly-constructed valve the platen T is lowered until another space is brought in a position to be filled by the charging-box, after which another division-plate S is placed on top of the meal so delivered. The platen T is then lowered to present another space to be filled by the charging-box, and this operation is repeated until the press is entirely filled. The charging-box D in its return or backward movement is stopped in proper position automatically by clutch mechanism and during which periods the platen is operated to present the spaces in proper position for said charging-box. When the press N is filled with meal or flour, as indicated above, the head-block or cover V is swung on its hinge V' to a position, as shown in Fig. 1, to fill the space in the top of the press through which the charging-box D moves in the op-

eration of filling the said spaces, and hydrostatic pressure is then applied to elevate the platen, and thereby compress the meal or flour into cakes of requisite density to impart thereto a breakable nature. After the material has been pressed for the proper length of time for it to form into such cakes the head-block V is released from its rigid position, due to the compression, by means of a screw a and wedge b, operated by hand-wheel c. The head-block or cover V is the exact shape of the cake and receives the pressure due to the upward movement of the ram or plunger P in the operation of compressing the cakes. This pressure renders it necessary to apply mechanical force in loosening said cover to move it in the position shown in Fig. 2 to permit of the removal of the cakes. The loosening of the said head or cover is obtained through the screw a and the wedge b. The removing or emptying operation is performed by elevating the ram or plunger P by hydrostatic pressure, and as each cake reaches the top of the press it is removed. The meal or flour while undergoing the cooking process is agitated or stirred by means of a suitable number of rotating arms e, which move over the bottom of the heater.

Having described our invention, we claim—

The herein-described method of treating oil-meal in the formation of soft cake for stock-feeding purposes, the same consisting in first grinding into meal hardened cakes originally solidified by pressure in the extraction of oil from the meal, then subjecting the reground meal to a cooking operation by the application of heat, supplying moisture to the substance during the heating or cooking thereof, and finally subjecting the cooked meal to a degree of pressure providing for the formation of a soft breakable cake, substantially as specified.

In testimony whereof we affix our signatures in presence of two witnesses.
